UNITED STATES PATENT OFFICE.

LESTER A. BUNDS, OF SANTA CLARA, CALIFORNIA, ASSIGNOR TO SAN JOSE SPRAY MFG. CO., OF SAN JOSE, CALIFORNIA, A CORPORATION OF CALIFORNIA.

PULVERULENT COPPER SULPHATE AND PROCESS OF PRODUCING SAME.

No Drawing.

Application filed December 17, 1923. Serial No. 681,086.

To all whom it may concern:

Be it known that I, LESTER A. BUNDS, a citizen of the United States, and a resident of Santa Clara, county of Santa Clara, 5 and State of California, have invented new and useful Improvements in Pulverulent Copper Sulphate and Processes of Producing Same.

My invention has for its object a preparation of copper sulphate as a powder which will retain its pulverulent condition free from agglomeration or lumping thus attaining a commercial article most readily soluble and particularly adapted to the mixing of insecticides, fungicides, etc., as for example that employed in the well known Bordeaux mixture.

Copper sulphate prepared by my method is most easily transported and handled and 20 available for quickly mixing into solutions prior to use.

The difficulty heretofore experienced has been that copper sulphate however finely it might be powdered or carefully prepared in 25 advance has been subject almost immediately thereafter to agglomeration into large masses, and especially so when brought into contact with water. It has thus been very difficult to dissolve in any quantity with or 30 without the lime mixtures ordinarily employed in spraying.

Copper sulphate prepared in accordance with my method is finely ground and during or immediately following the grinding 35 there is incorporated therewith a sufficient amount of an inert powder, as talc or the like, whereby the particles of copper sulphate are coated sufficiently to hold them separate from each other, thus preventing 40 their subsequent agglomeration. In order to secure the coating of each particle of copper sulphate in any given mass, it is necessary to first separate these particles and then inject the talc or any other inert 45 powder therebetween, and thoroughly coat the particles of copper sulphate with the powder. This I prefer to accomplish as follows:

In order to effect a proportionate feed of 50 talc and copper sulphate into the grinding and mixing chamber, the required amount of talc is first thoroughly hand mixed with the copper sulphate on a mixing floor. The resulting mixture is then fed into the grinder or disintegrator. Here the cyclone

of air currents set up combined with the multiple hammer blows of the mill rotor, separate the talc from the large crystals of copper sulphate and more intimately mix it with the finely divided particles resulting from the mill action. As these two materials leave the mixing chamber they pass through a fan and conducting pipe, preferably in a relatively strong current of air, into an expansion chamber where the particles of talc and copper sulphate are given a gentle rotating and rolling motion. It is here that the relatively large particles of crystalline copper sulphate are actually rolled in talc thus effecting a thorough 70 coating of each particle and producing a bluestone powder which is without tendency to harden, pack or ball up.

In this way the talc is brought into contact with every particle of the copper sulphate surfaces so that each particle is separated by the talc from every other particle, resulting in a mixture of bluestone powder which is without tendency to harden either during subsequent handling, transporting or mixing and is easily soluble.

If an inert powder other than talc be used, I have found it advisable that it be chosen with respect to its solubility which in each case should be less than that of copper sulphate and it must be of a nonhygroscopic nature and free from any impurities having hygroscopic qualities.

The final mixture will then consist at all times of copper sulphate particles separated 90 from each other by foreign dry and inert particles whereby when water is added for the final solution it most readily reaches every particle of the copper and the greatest solubility of the copper sulphate in the mixture will be retained.

Reference is herein made to my co-pending application No. 23,026, filed April 14, 1925.

I claim:

1. The method of preparing a readily soluble copper sulphate mixed with an inert substance which consists in grinding the inert substance to a finer mesh than the copper sulphate and then blowing the copper sulphate and the substance through a tube whereby the particles of copper sulphate are separated from each other and the substance is admitted between the surfaces of the copper sulphate particles.

2. The method of preparing a readily soluble copper sulphate mixed with an inert substance which consists in grinding the inert substance to a finer mesh than the copper sulphate and then blowing the copper sulphate and the substance through a tube whereby the particles of copper sulphate are separated from each other and the substance is admitted between the surfaces of the copper sulphate particles and thereafter 10 agitating the mixture whereby the substance is caused to adhere between the particles of copper sulphate.

LESTER A. BUNDS.
